APPARATUS FOR TREATING ONE LIQUID
WITH ONE OR MORE OTHER LIQUIDS

Harold Moore, London, England

Application December 9, 1937, Serial No. 179,020
In Great Britain December 14, 1936

5 Claims. (Cl. 23—270.5)

This invention relates to an improved apparatus for continuously treating one liquid with another or for continuously treating one liquid successively with other liquids, and whilst not limited in its application is more particularly intended for washing, solvent treating, deodorising or desulphurising mineral oils and other hydrocarbon liquids.

The admixture and separation of two liquids 10 by first passing them through a suitable pump and continuously returning them through the same pump and delivering the liquids after admixture to a separating vessel is known and the apparatus has comprised two or more treating 15 units, each unit comprising a separating vessel and a pump to circulate the liquids to be admixed through pipe-lines leading from the delivery of the pump back to the suction of the same pump and independent of the separating 20 vessels, a bleed line to allow the admixed liquids to escape from the pump circuit to the separating vessel and pipe-lines from the upper and lower ends of the separating vessel to allow the lighter and heavier liquids respectively to escape from 25 the separating vessel, an orifice either variable or fixed, or other device constricting the flow of the liquids being arranged in the pump circuit in such manner as to create a pressure in the separating vessel and in pipe-lines leading from the 30 separating vessel. Also the bleed line might be disposed in relation to the separating vessel so that the liquids enter the separating vessel in a direction tangential to its side at the point of entry and that if desired a mixing vessel, either 35 open or closed to the atmosphere, might be inserted in the pump circuit.

My invention consists in the provision of one or more treating units, each unit comprising a separating vessel, a circulating pump, a bleed line, an orifice or other device constricting the flow of the liquids, pipe-lines from the upper and lower ends of the separating vessel and a mixing vessel as included in prior apparatus, and a variable capacity pump or similar device such for 45 example as disclosed in British Patent No. 476,953, which can be so adjusted as to charge the treating liquid to the mixing vessel at a rate of flow bearing a fixed proportion to that at which the liquid to be treated enters the unit or series 50 of units, an automatic level controller operated by mechanical, electrical, pneumatic or other means to control the height of the liquids in the mixing vessel by varying the volume of admixed liquids entering the separating vessel via the 55 bleed line. The pipe-line from the lower end

of the separating vessel is connected to an overflow, weir, or similar arrangement, such that the level of the point of overflow may be adjusted in order to control the vertical height of the surface of separation in the separating vessel. The mixing vessel, separating vessel and overflow, weir or similar arrangement, may be either open to the atmosphere via vent pipes or the like, or may be connected to a common pipe line system.

According to the present invention the liquid to be treated is charged continuously to the mixing vessel of one unit. The first treating liquid is also charged to the mixing vessel or to the mixing vessel of another unit of the same series, by 15 means of a pump or device which can be so adjusted as to maintain a fixed proportion between the quantities of liquid and treating liquid charged to the treating unit, or series of treating units.

After first passing through the circulating pump the liquids are continuously returned to the mixing vessel and passed through the pump thus giving any desired degree of admixture. After passing through the pump the admixed 25 liquids exert a pressure in the bleed line and after admixture by the pump, as previously described, a portion enters the separating vessel in such manner as to impart a rotating motion to its contents as described in previously proposed apparatus. The effective height of the overflow, weir, or similar arrangement connected to the pipe-line from the bottom outlet of the separating vessel may then be adjusted in order to control 30 the height of the surface of separation in the 35 separating vessel.

From the upper end of the separating vessel the lighter liquid may be overflowed, and may pass by gravity or other means to the mixing vessel of a succeeding unit or alternatively to 40 storage, while the heavier liquid may be allowed to pass over the overflow, weir, or similar arrangement, through pipe lines from the lower end of the separating vessel, passing by gravity or other means to the mixing vessel of a preceding 45 unit or alternatively to storage, or vice versa, the operation throughout being continuous.

The object of varying the position of the overflow, weir or similar arrangement connected to the pipe line leading from the bottom outlet of 50 the separating vessel, is to provide means for controlling the height of the surface of separation in the separating vessel. Further, the liquids may be allowed to flow by gravity alone from the upper and lower ends of the separating vessel 55

or vessels and consequently equal pressures may be maintained in the mixing vessel and separating vessel or in the mixing vessels and separating vessels of a series of units, thus greatly facilitating the operation of the process. The mixing vessel, separating vessel and overflow, weir or similar arrangement, or the mixing vessels, separating vessels and overflows, weirs or similar arrangements, of interconnected units, may remain open to the atmosphere by the provision of vent pipes or the like, or, alternatively, they may be connected to a common pipe line system, the pressure in which is controlled in order to reduce or prevent evaporation of the liquids, or which system may contain inert gases as a security against fire or against oxidation of the liquids.

In order to provide means for continuously treating one liquid counter currently with another liquid in two or more stages, and if desired successively with more than one other liquid, treatment with each liquid being performed in any desired number of stages, a series of units each as previously described is provided, the upper and lower ends of each separating vessel, however, not being permanently connected by means of pipe lines to the mixing vessels of succeeding and preceding units or vice versa, there being further no permanent connection between the variable capacity pump or similar device and the mixing vessel of each unit. Connections between units and between any variable capacity pump and any mixing vessel within the series may be made by means of flexible hoses, manifolds, or the like in known manner and the treating circuit can then be arranged so as to treat the liquid with a succession of different treating liquids. Treatment with each liquid in turn may be performed counter-currently employing as many stages as may be desired, provided that the total number of treating stages does not exceed the number of interconnected treating units. In a battery of units several single systems or multiple systems, even treating different liquids, may be operated simultaneously.

Reference will now be made to the accompanying drawings which illustrate by way of example a construction according to the invention, in which Fig. 1 is an elevation showing the improved treating unit and Fig. 2 is an elevation showing the manner in which three such units may be arranged in order to treat a liquid counter-currently and successively with two treating liquids.

In the form illustrated in Fig. 1 and taking by way of example the washing of kerosene with a liquid of higher density, the improved treating unit may be constructed in the following manner:

Connected to the suction and delivery of the circulating pump 1 is a mixing vessel 2. Delivering into the mixing vessel are a pump 3 and a variable capacity pump or similar device 4. The purpose of the pump 3 is continuously to deliver the kerosene to be treated to the unit, and the purpose of the variable capacity pump or similar device 4 is continuously to deliver a quantity of the liquid of higher density bearing a fixed proportion to the quantity of kerosene delivered.

Interposed between the suction and delivery of the pump 1 is an orifice or similar constricting device 5. From the delivery side of the pump circuit between the pump and the orifice, a bleed line 6 is led to a vertical separating tank 7 of the form illustrated. The bleed line is so disposed in relation to the vertical separating vessel 75 that the liquids enter the tank in a direction

tangential to its side, as proposed in previously described apparatus.

The level of liquid in the mixing vessel is controlled by means of a liquid level controller 8, which operates a valve 9 situated in the bleed line, so as to control the volume of liquid entering the separating vessel. From the lower end of the separating vessel a pipe line 10 is led to an overflow, weir, or similar device 11, so arranged that the position of the point of overflow relative to the separating vessel may be varied in order to control the position of the surface of separation in the separating vessel. The overflow, weir or similar device is connected to a pipe line 12, through which the heavier liquid may be allowed to flow. The upper end of the separating vessel is provided with a pipe line 13, through which the kerosene may be overflowed. The mixing vessel, separating vessel and overflow are provided with pipe lines 14, 20 either open to the atmosphere or connected to a common pipe line system.

In operation and considering firstly the continuous treatment of kerosene with a liquid of heavier density in one treating stage, the unit is 25 operated in the following manner:

The kerosene is continuously charged to the mixing vessel 2 by means of pump 3, while simultaneously heavier liquid is continuously charged by means of the variable capacity pump or similar device 4, which latter is so adjusted that a fixed proportion is maintained between the quantities of kerosene and heavier liquid delivered to the mixing vessel. The two liquids are continuously withdrawn from the base of mixing 30 vessel 2 by means of the circulating pump 1, and are continuously returned to the mixing vessel after passing through the orifice or similar constricting device 5.

If desired the admixed liquids may be caused 40 to impinge on a baffle 15, placed in the mixing vessel. When the admixed liquids in the mixing vessel reach a predetermined level the liquid level controller 8 actuates the valve 9, allowing a portion of the admixed liquids to enter the separating vessel via the bleed line 6, which is so disposed in relationship to the separating vessel that the admixed liquids enter the separating vessel in a direction tangential to its side at the point of entry. After the liquids have reached the 50 predetermined level in the mixing vessel, this level is automatically maintained therein by the liquid level controller 8, which controls by means of valve 9 the rate at which the admixed liquids enter the separating vessel.

As the admixed liquids enter the separating vessel, liquid will rise in pipe line 10 and the position of the overflow, weir or similar device 11 is then adjusted in order to control the position of the surface of separation in the separating vessel. After suitable adjustment of the overflow, weir, or similar device, the surface of separation may be maintained at any desired level in the separating vessel, heavier liquid flowing continuously via the overflow, weir, or similar device through pipe line 12, treated kerosene flowing continuously by gravity through the pipe line 13, the operation throughout being continuous and under automatic control.

In order to provide means for continuously 70 treating one liquid counter-currently with another liquid in two or more stages, and if desired successively with more than one other liquid, a series of units, each as previously described, is provided there being, however, no permanent connection between the upper and lower outlets 75

of each separating vessel, or between the variable capacity pump and mixing vessel of each unit. Connections between units and between variable capacity pumps and mixing vessels may 5 be made by means of flexible hoses, manifolds or similar devices in known manner, and the treating circuit can be arranged to suit requirements. Further, when a series of units is provided, more than one treating circuit can be arranged, if desired, in order to treat more than one liquid 10 with one or more other liquids, treatment with each liquid in turn being performed in one or more units.

In the form illustrated in Fig. 2 and taking 15 by way of example the washing of kerosene with two liquids of higher density, three treating units A, B and C, each constructed as previously described, are provided, each being connected in the following manner, connections made by flexible hoses, manifolds or the like being shown by broken lines on accompanying figure:—

Pump 3 is arranged so as to deliver kerosene 20 into the mixing vessel 2A. Pipe line 13A from the upper end of separating vessel 7A is connected to mixing vessel 2B and pipe-line 12A leading from the overflow, weir or similar arrangement, of unit A is connected either to waste or to storage. Pipe line 13B leading from the upper end of the separating vessel 7B is connected to the mixing vessel 2C and pipe-line 12B leading from the overflow, weir or similar arrangement of unit B is connected to mixing vessel 2A. Variable capacity pump 4B is arranged 25 so as to deliver the first treating liquid to mixing vessel 2B. Pipe-line 13C is connected to pipelines leading to storage and pipe line 12C is connected either to waste or to storage. Variable capacity pump 4C is arranged so as to deliver the second treating liquid to mixing vessel 2C.

40 In the arrangement illustrated in Fig. 2 there is no communication between variable capacity pump 4A and any portion of the treating unit. When, however, it is desired to use the three treating units A, B and C in order to treat, for 45 example kerosene with three liquids of higher density, variable capacity pump 4A may be connected to mixing vessel 2A whilst pipe-line 12B is connected either to waste or to storage.

In operation and considering firstly the function 50 of units A and B, kerosene to be treated is continuously charged to mixing vessel 2A by means of the pump 3. The first treating liquid is continuously charged to mixing vessel 2B by means of the variable capacity pump 4B, which 55 is so adjusted that the quantities of first treating liquid and kerosene bear a fixed and constant proportion to each other.

Once used first treating liquid flows to mixing vessel 2A via pipe-line 12B, kerosene and once 60 used first treating liquid are then continuously withdrawn from mixing vessel 2A by pump 1A and are continuously returned to the mixing vessel after passing through the orifice or similar constricting device 5A. When the liquids in 65 mixing vessel 2A reach a predetermined level, liquid level controller 8A actuates the valve 9A, allowing a portion of the admixed liquids to enter the separating vessel 7A, in a direction tangential to its side at the point of entry.

70 The position of the surface of separation in separating vessel 7A is then controlled by adjusting the position of the overflow, weir or similar arrangement 11A, when twice used first treating liquid flows via pipe-line 12A either to waste or to storage, and once treated kerosene 75

flows via pipe-line 13A to mixing vessel 2B. When the admixture of once treated kerosene and fresh first treating agent in mixing vessel 2B reaches a predetermined level, the level controller 8B actuates the valve 9B allowing a portion of the admixed liquids to enter the separating vessel 7B via the bleed line 6B. The position of the surface of separation in the separating vessel 7B is controlled by adjusting the position of overflow, weir, or similar arrangement 11B and twice treated kerosene leaves separating vessel 7B via pipe line 13B.

Considering secondly the operation of unit C, the second treating liquid is delivered to mixing vessel 2C by variable capacity pump 4C, while 15 kerosene twice treated with the first treating agent flows to mixing vessel 2C via pipe line 13B. After continuous admixture and separation with the second treating liquid in the previously described manner, once used second treated liquid 20 is allowed to flow via pipe line 12C to waste or to storage and kerosene counter-currently treated in two stages with the first treating liquid and treated in one stage with the second treating liquid may be overflowed via pipe line 13C, 25 either to storage or to receive treatment in further treating units, the operation throughout being continuous and under automatic control.

I claim:

1. An apparatus for treating one liquid with another liquid of different density comprising as a unit, a mixing vessel, means for continuously charging said mixing vessel with a light liquid and a heavy liquid, at least one of said charging means being of variable capacity whereby said liquids are supplied at rates of flow bearing a predetermined proportion to each other; a pump; a line interconnecting the intake of said pump and said mixing vessel, a second line interconnecting the outlet of said pump and said mixing vessel; orifice means for creating back pressure in said second line; a separating vessel; a third line interconnecting the outlet of said pump and said separating vessel and having a valve therein; means automatically operated by the liquid level in said mixing vessel for opening said valve and allowing the admixed liquids to flow to said separating vessel when the liquids attain a predetermined level in said mixing vessel, and for closing said valve when said liquids fall below a predetermined level, thereby automatically maintaining a constant level in said mixing vessel irrespective of the rates of flow of liquids into said mixing vessel; and lines leading from the upper and lower portions of said separating vessel for the discharge of said light and heavy liquids respectively; said line for the discharge of the said heavy liquid terminating in an outlet of adjustable height whereby the level of the surface of separation between the liquids in the separating vessel may be adjusted.

2. Apparatus according to claim 1 for the continuous countercurrent admixture and separation of liquids of differing densities, comprising a plurality of said units and including means conducting the lighter liquid from the upper end of the separating vessel of one unit to the mixing vessel of a succeeding unit, and means for conducting the heavier liquid from the lower end of said separating vessel to the mixing vessel of a preceding unit.

3. Apparatus according to claim 1 for the continuous admixture and separation of a liquid to be treated with a plurality of treating liquids of

densities differing from that of the liquid to be treated, comprising a series of said units including means for supplying the treating liquids of different densities to the mixing vessels of the respective units, means for continuously conducting the liquid to be treated from the separating vessel of each unit to the mixing vessel of a succeeding unit in the series, and means for continuously discharging the treated liquid from the separating vessel of the last unit in the series.

4. Apparatus according to claim 1, comprising a series of said units wherein the variable ca-

pacity means of the different units supply different treating liquids, and including means for interconnecting the variable capacity means of any unit to the mixing vessel of any other unit in the series.

5. Apparatus according to claim 1, comprising a series of said units and including means for interconnecting the pipe lines from the upper and lower ends of the separating vessel of one unit to the mixing vessels of other units in the series.
